RAILWAY OBSERVATION CAR BODY

Alfred B. Girardy, Chicago, Donald W. Doman, Harvey, and Ralph E. Meyers, Niles, Ill., assignors to Pullman-Standard Car Manufacturing Company, Chicago, Ill., a corporation of Delaware

Application December 13, 1950, Serial No. 13,417

Term of patent 14 years

(Cl. D66—1)

To all whom it may concern:

Be it known that we, Alfred B. Girardy, Donald W. Doman, and Ralph E. Meyers, citizens of the United States of America and residents, respectively, of Chicago, county of Cook, and State of Illinois, Harvey, county of Cook, and State of Illinois, and Niles, county of Cook, and State of Illinois, have invented a new, original, and ornamental Design for a Railway Observation Car Body, of which the following is a specification, reference being had to the accompanying drawings, forming part thereof.

In the drawings:

Fig. 1 is a general perspective view of our new design for a railway observation car body;

Fig. 2 is a side elevational view thereof;

Fig. 3 is a plan view of the car body;

Fig. 4 is an end elevational view thereof;

Fig. 5 is a cross sectional contour view taken on the line 5—5 of Fig. 2;

Fig. 6 is a cross sectional contour view taken on the line 6—6 of Fig. 2;

Fig. 7 is a cross sectional contour view taken on the line 7—7 of Fig. 2; and

Fig. 8 is a cross sectional contour view taken on the line 8—8 of Fig. 2.

The end of the car body opposite that shown in Fig. 4 has not been illustrated, but is of conventional design. The dotted line representations in the several figures of the drawings are for illustrative purposes only.

What is claimed is:

The ornamental design for a railway observation car body, substantially as shown and described.
